CLAIM

The ornamental design for a combined flag display case and memorial plaque, as shown and described.

DESCRIPTION

FIG. 1 is a perspective view of the combined flag display
and memorial plaque showing my new design;
FIG. 2 is a perspective view of a second embodiment of
FIG. 1, the eagles being in a prone position and the flag and service insignia shown in broken lines for illustrative purposes only;

FIG. 3 is a reduced top view of FIG. 1;

FIG. 4 is a reduced front view of FIG. 1;

FIG. 5 is a reduced rear view of FIG. 1;

FIG. 6 is a reduced bottom view of FIG. 1;

FIG. 7 is a reduced left side view of FIG. 1;

FIG. 8 is a reduced right side view of FIG. 1.
